UNITED STATES PATENT OFFICE

133,971

DESIGN FOR A DISPLAY UNIT

Alexander Emery, River Forest, Ill., assignor of
one-half to A. Arnold Brand, Oak Park, Ill.

Application March 11, 1942, Serial No. 106,153

Term of patent 7 years

To all whom it may concern:

Be it known that I, Alexander Emery, a citizen of the United States, residing at River Forest, in the county of Cook and State of Illinois, have invented a new, original, and ornamental Design for a Display Unit, of which the following is a specification, reference being had to the accompanying drawing, forming a part thereof.

Fig. 1 is a perspective view of a display unit, showing my design; and

Fig. 2 is a front elevational view thereof.

The characteristic features of the design are shown in full lines in the drawing.

I claim:

The ornamental design for a display unit, substantially as shown and described.

ALEXANDER EMERY.
